UNITED STATES PATENT OFFICE.

LESLIE HURST PETER, OF LONDON, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed December 26, 1924, Serial No. 758,068, and in Great Britain February 29, 1924.

My invention relates to railway signaling apparatus of the kind in which the signals are of the illuminated or light type adapted to give one or another of two or more different signal indications, and has for its object to provide simple and effective arrangements for electrically transmitting to any desired point an indication of the particular signal or signals which is or are operative at any time.

According to my present invention this is effected by causing the phase or magnitude of an electric current transmitted from the signal to the point at which indication is desired to be varied in accordance with the particular signal or signals which is or are operative this current being supplied to an indicating device which is so constructed as to be responsive to the phase or magnitude of the current.

My invention is illustrated by way of example in the accompanying drawings, of which Figs. 1 to 7 inclusive are diagrammatic views of various arrangements of apparatus which may be employed in carrying my invention into practice.

Referring now first to the arrangement shown in Fig. 1, it will be seen that a signal actuating apparatus S is provided comprising a local energizing winding 1 and a control winding 2, the winding 1 being permanently connected to a source of alternating current which may be constituted by transmission conductors. The winding 2 is also supplied with alternating current from the same or another source, the current traversing this winding being controlled from any suitable point such as a signal cabin, so as to cause the signal apparatus S to give one or another of three different illuminated signal indications. For instance, the signal apparatus S may be arranged to effect the setting of a signal arm spectacle so as to bring one or another of three differently colored discs in front of the signal lamp in the usual manner. The operation of the signal apparatus S is indicated at the point of control or other selected point by means of an indication device I which may comprise, as indicated diagrammatically, a power factor meter having an element 50 connected with a source of energy of known phase relation with respect to the source connected with winding 1 and

adapted to give four different indications, viz, one when the current supplied to the device I is zero, a second indication when this current is of unity power factor, a third indication when the current has a lagging power factor, and a fourth indication when the current has a leading power factor.

The indication device I is connected to the signal apparatus S by two conductors 3, 4, one, 3, of which is connected to one of the terminals of the winding 1. An intermediate point in this winding is connected by means of a conductor 5 through switch contacts 6 to a contact arm 7 adapted to be operated by the signal arm carrying the spectacle above referred to.

The switch contacts 6 are arranged to be closed only when the signal lamp is illuminated and the contact arm 7 is arranged to engage with one or other of three fixed contacts 8, 9 and 10, according to the signal indication exhibited, that is to say, according to the position of the signal arm spectacle.

The contact 8 is connected through an inductive resistance 11 to the conductor 4, the contacts 9 and 10 being also connected to the same conductor through a non-inductive resistance 12, and a condenser 13 respectively.

In operation it will be understood that when the signal lamp of the apparatus S is not illuminated the switch contacts 6 are open and current is consequently not supplied to the indication device I, and the latter accordingly gives a corresponding indication. If, however, the signal lamp is illuminated so that the contacts 6 are closed and the signal arm spectacle occupies a position corresponding, for instance, to a "danger" signal indication the contact arm 7 being in the position shown in the figure that is to say, is in engagement with the contact 9, current is supplied from the winding 1 to the indication device I, and owing to this circuit including the non-inductive resistance 12 this current will be of unity power factor. The indication device I will accordingly give the second or "danger" indication above referred to.

In the event of the signal arm spectacle occupying a position in which the contact arm 7 is in engagement with the contact 8 corresponding, say, to a "caution" signal indication, the current supplied to the indi-

cation device I will traverse the inductive resistance 11, and will consequently have a lagging power factor, so that the device I will give the third indication.

5 Finally, if the signal arm spectacle assumes a position in which the contact arm 7 is in engagement with the contact 10, corresponding, say, to a "proceed" signal indication, the current supplied to the indication device I will traverse the condenser 13 so that this current will have a leading power factor and the device I will give the fourth indication.

It will thus be seen that four different 15 conditions or settings of the signal apparatus S can be indicated at the desired point by the use of two transmission conductors connecting this point to the signal apparatus S.

20 In the arrangement shown in Fig. 2, the same result can be achieved with a single conductor 4 connecting the signal apparatus S to the indication device I, the other terminal of the latter device being connected by 25 a conductor 14 to the middle point of an inductive bridge 15 connected across the control conductors 16 leading from the point of control to the winding 2.

The middle point of the latter winding is 30 connected by means of a conductor 41 to an intermediate point in the winding 1, and the conductor 5 is connected to one of the terminals of the winding 1, as indicated in the figure.

35 The operation of the arrangement shown in Fig. 2 is the same as that described above with reference to Fig. 1, it being understood that one of the conductors connecting the signal apparatus S to the indication device I is constituted by a "phantom" circuit 40 through the conductors 16.

In the arrangement shown in Figs. 1 and 2 it will be seen that the indication device I is adapted to be operated to give different 45 indications in accordance with the phase of the current transmitted thereto from the signal apparatus S. The different positions of the signal arm spectacle may, however, be indicated at the point of control by varying the 50 voltage of the current transmitted to the indication device as in the system illustrated diagrammatically in Fig. 3.

In this arrangement the contacts 8, 9 and 55 10 one or another of which is adapted to be engaged by the contact arm 7 in accordance with the position of the spectacle, are connected by means of conductors 17, 18, 19 respectively to points of different voltage in an alternating current transformer winding 60 which may, as shown, be the winding 1 of the signal apparatus S.

The indication device I is in this case constructed as a voltmeter or ammeter, being thus capable of giving different indications 65 in accordance with the particular signal

which is operative at a time. In other respects the operation is the same as that of the arrangement above described and will be obvious from the drawing.

The arrangement shown in Fig. 4 is similar to that of Fig. 3, except that a "phantom" 70 return circuit is utilized as in the arrangement shown in Fig. 2.

Referring now to the arrangement shown in Fig. 5 which is similar to that of Fig. 1, 75 the signaling apparatus S is shown as comprising three signal lamps 20, 21, 22, adapted to give correspondingly different signal indications, each of these lamps being provided with its own energizing circuit conductor 23, 24, 25, and a common return conductor 26. The circuit of each of the lamps 20, 21, 22 includes the winding of a relay, the movable contacts 27, 28, 29 of which are adapted when the relays are energized to 80 engage with fixed contacts 8, 9, 10 respectively, and thus complete a circuit from the secondary winding 30 of a transformer through an inductive resistance 11 or a non-inductive resistance 12 or a condenser 13, 85 according as the lamp 20 or the lamp 21 or the lamp 22 is operative. One terminal of the transformer winding 30 is connected to the common conductor 31 and the other terminal to the conductor 4 leading to the 90 indication device I. The other indication conductor 3 is connected to the relay contacts 27, 28, 29 and the primary winding 32 of the transformer is connected to any suitable source of alternating current.

In operation it will be understood that when none of the signal lamps 20, 21, 22 is supplied with operating current all the relays are de-energized, and current is not supplied from the transformer winding 30 to the 95 indication device I, which accordingly gives a corresponding indication.

If, however, one or other of the lamps 20, 21, 22 is energized current of lagging, unity, or leading power factor will be transmitted to the device I, and a corresponding 100 indication given.

The arrangement shown in Fig. 6 is similar to that shown in Fig. 3, except that one or another of the points of different voltage in the transformer winding 1 is arranged to be connected to the conductor 4 leading to the indication device I when a corresponding relay contact 27, 28, 29 is closed, this relay being energized when current is supplied 110 to the corresponding signal lamp 20, 21, or 22.

The conductor 3 leading to the indication device I in this case also serves as a return conductor for the signal lamp circuits as 115 will be readily understood.

Referring now to the arrangement shown in Fig. 7 the indication device I employed is in this case of the direct current type being adapted to give one on another of four 120

different indications according as the device is deenergized or traversed by current of one polarity and normal value, or by current of opposite polarity and reduced value, 5 or by current of such opposite polarity and of normal value.

A rectified alternating current supplied from the secondary 33 of a transformer the primary of which may be the winding 1, is 10 employed for operating the indication device I, one terminal of the secondary 33 being connected through a conductor 34, a rectifier 35 and a conductor 36 to a fixed contact 8. The other terminal of the secondary 33 is connected through a conductor 37, a rectifier 38, a conductor 39 and a resistance 40 to a second fixed contact 9, the conductor 39 being also connected to a third fixed contact 10, as shown in the drawing. 15 The middle point of the secondary 33 is connected to the indication conductor 4 and the middle point of the winding 2 is connected through switch contacts 6 to a contact arm 7 adapted to engage with one or another 20 of the fixed contacts 8, 9, 10. The contact arm 7 is arranged to be operated in accordance with the movement of the signal arm spectacle as above described with reference to Fig. 1.

30 In operation it will be understood that when the signal lamp is not illuminated the contacts 6 are open so that current is not supplied to the indication device I which accordingly gives a corresponding indication.

When the spectacle occupies a position corresponding to a "danger" indication the contact arm 7 is in engagement with the fixed contact 8 so that current is supplied 40 from the secondary 33 through conductor 34, rectifier 35, conductor 36, fixed contact 8, contact arm 7, closed switch contacts 6, the two halves of the winding 2 and the conductors 16 and inductive bridge 15 to the indication device I, the return circuit being from the conductor 4 to the middle point of the secondary 33.

The rectifiers 35 and 38 are each arranged to suppress different halves of the alternating current wave, the rectifier 35 being, for instance, arranged to suppress the negative half with the result that the current traversing the indication device through the circuit above described will be of positive polarity and will operate the indication device I accordingly.

When the signal arm spectacle occupies a position corresponding to "caution" the contact arm 7 will be in engagement with the fixed contact 9, so that a circuit will be completed from the secondary 33, through conductor 37, rectifier 38, conductor 39, resistance 40, fixed contact 9, contact arm 7, and switch contacts 6 to the indication device I 65 as above described. The rectifier 38 being

adapted to suppress the positive halves of the alternating current wave it will be clear that the current supplied to the indication device I in these circumstances will be of negative polarity, and since the circuit traversed by this current includes the resistance 40 will be of less than the normal value thus giving a corresponding indication at the device I.

70 When the signal arm spectacle occupies a position corresponding to "proceed" the contact arm 7 will be in engagement with the fixed contact 10, whereupon current of negative polarity will flow from secondary 33, through conductor 37, rectifier 38, conductors 39 and 39, fixed contact 9, contact arm 7, and switch contacts 6 to device I as above described, the resistance 40 in this case, however, not being included in the circuit so that the current supplied to the indication device 80 will be of negative polarity and of normal value, and will cause a corresponding indication at this device.

85 The rectifiers indicated at 35, 38 are preferably of the type described in the specification of British Patent No. 194,653.

90 It will be understood that various modifications of the arrangements above described may also be employed for instance, in the case in which each signal indication 95 is given by a separate lamp the relay connected in the lamp circuit may be replaced by a thermo-sensitive device arranged adjacent to the lamp so that the heat generated thereby when the lamp is operative will cause the closure of contacts for varying the character of the current transmitted to the indication device.

100 Again, it will be evident that multiple aspect working of the signal can be indicated, if desired, the indicating device, whether of the power factor meter, voltmeter or ammeter type, being adapted to give an indication intermediate those of two signal lamp aspects. For instance, in the case in which 105 the multiple signal aspect comprises the simultaneous operation of two signal lamps such, for instance, as the lamps 20, 21 and 22, the multiple aspect corresponding to the simultaneous operation of these lamps will 110 cause an indication current having a power factor corresponding to a lead of 45° in phase to be transmitted to the indication device and a corresponding indication given thereby.

115 In these and other respects my invention is not limited to the particular arrangements above described and illustrated by way of example, which may be varied as desired in order to meet particular conditions without exceeding the scope of my invention.

120 Having now particularly described and ascertained the nature of my said invention and in what manner the same is to be performed, I declare that what I claim is:

1. In combination, a signal capable of displaying three indications, an indicator responsive to the phase of the current supplied thereto, and means for connecting said indicator with a source of alternating voltage through a non-inductive resistance, an inductive resistance or a condenser depending upon the indication displayed by the signal.
- 10 2. In combination, a signal capable of displaying three indications, an indicator responsive to the presence or absence of current supplied thereto and also to the phase relation of the current supplied thereto, a source of energy having one terminal con-

stantly connected with one terminal of said indicator, a non-inductive resistance, an inductive resistance and a condenser each having one terminal constantly connected with the remaining terminal of said indicator, a movable contact connected with the remaining terminal of said source when said signal displays any one of said indications and arranged to engage the free terminal of said non-inductive resistance said inductive resistance or said condenser depending upon the indication displayed by the signal.

In testimony whereof I affix my signature.

LESLIE HURST PETER.
